COMBINED PLAYGROUND ROUNDABOUT,
TEETER BOARD, AND CLIMBING LAD-
DER OR SIMILAR ARTICLE

Robert E. Martens, Charleston, W. Va.

Application January 11, 1955, Serial No. 33,923

Term of patent 3½ years

(Cl. D34—5)

Fig. 1.

Fig. 2.

Fig. 3.

Fig. 4.

Figure 1 is a top plan view of a combined playground roundabout, teeter board and climbing ladder or similar article showing my new design;

Figure 2 is a side elevation thereof, the opposite side view being the same;

Figure 3 is an end elevation thereof viewed from the left in Figure 2; and

Figure 4 is an end elevation thereof viewed from the right in Figure 2.

The broken line showing of a mooring base is for illustrative purposes only.

I claim:

The ornamental design for a combined playground roundabout, teeter board and climbing ladder or similar article, as shown and described.
